UNITED STATES PATENT OFFICE.

JAMES A. MOORE, OF HAMILTON, ASSIGNOR TO MARK C. MOORE, OF BUNKER HILL, OHIO.

HARROW.

SPECIFICATION forming part of Letters Patent No. 391,380, dated October 16, 1888.

Application filed January 3, 1888. Serial No. 259,622. (No model.)

To all whom it may concern:

Be it known that I, JAMES A. MOORE, of Hamilton, Butler county, Ohio, have invented certain new and useful Improvements in Harrows, of which the following is a specification.

This invention pertains to folding harrows, and relates to the arrangement of runners whereby two runners are brought into operative position by manipulating a single folding section.

My improvements will be readily understood from the following description, taken in connection with the accompanying drawings, in which—

Figure 1 is a plan of a harrow illustrating my improvements, the harrow appearing as open for use; Fig. 2, a side elevation of the same; Fig. 3, a rear elevation of the same, the runner-section appearing as folded upon the top of the non-folding section, and Fig. 4 a perspective view exemplifying the latching for supporting the non-folding section. Figs. 3 and 4 are upon an enlarged scale.

In the drawings, A indicates the non-folding section of the harrow, the same being formed of toothed timbers and cross-ties, as usual; B, the folding section, similar in general construction to the section A; C, hinges uniting the sections A and B, so as to permit the section B to be folded over flat on top of the section A when the harrow is to be transported from the field; D, the outer timber of the folding section B; E, the inner timber of the same section; F, a runner rigidly secured to and projecting upwardly from the outer timber of the folding section B; G, a similar runner similarly secured to the inner timber, E; H, latching parts secured, respectively, to the non-folding section and to the folding section B, and adapted, when the folding section is folded over flat upon the top of the non-folding section, to prevent the separation of the sections; and J, a second folding section hinged to the non-folding section in a similar manner to the folding section B, and adapted, after the section B is folded over upon the top of the non-folding section, to be folded over flat upon the top of the section B.

If the folding section B be folded over flat upon the top of the non-folding section A, the runners F and G will clear the timbers of the non-folding section, and will pass onward down to the ground and rest upon the ground with the teeth of the folding section projecting upwardly, as indicated in Fig. 3. The non-folding section may now be lifted until it lies closely against the section B, when the latching will engage and the non-folding section be free of the ground, so as to permit the harrow, if of two sections only, to be freely transported from field to field, &c. The second folding section, J, if employed, is to be folded over the folding section B.

In Fig. 3 the parts are shown as they would appear after the folding section B has been folded upon the non-folding section and latched, and just before the second folding section, J, is folded over.

When desired for use in the field, the second folding section, J, if present, is first unfolded and takes the position indicated in Fig. 3. The latching are then disengaged, which permits the dropping of the non-folding section, after which the folding section B is unfolded into the position shown in Fig. 1. The harrow is to be hitched to in any of the usual applicable manners.

I claim as my invention—

In a harrow, the combination, with a non-folding section and a folding section hinged together so that the folding section may be folded over down flat upon the top of the non-folding section, of a runner secured to and rigidly projecting upwardly from the top of the free edge of the folding section, a second runner similarly secured to and rigidly projecting upwardly from the inner edge of the folding section, and a latching adapted to hold the two sections together when folded, substantially as and for the purpose set forth.

JAMES A. MOORE.
